(57) **CLAIM**

The ornamental design for a food container assembly, as shown and described.

DESCRIPTION

FIG. 1 is a top and front perspective view of a food container assembly showing our new design.

FIG. 2 is top plan view thereof.

FIG. 3 is a bottom plan view thereof.

FIG. 4 is a first side elevation view thereof.

FIG. 5 is a second side elevation view thereof; and,

FIG. 6 is representative of the third and fourth side elevation views thereof.

The portions of the food container assembly not shown form no part of the claimed design.
